US0D1031313S

(12) **United States Design Patent** (10) **Patent No.:** **US D1,031,313 S**
(45) **Date of Patent:** **** Jun. 18, 2024**

(54) **SEAT CUSHION**

(71) Applicant: **Cushion Lab LLC**, Wilmington, DE (US)

(72) Inventor: **Wen Hao Tuan**, Taipei (TW)

(73) Assignee: **CUSHION LAB LLC**, Wilmington, DE (US)

(**) Term: **15 Years**

(21) Appl. No.: **29/806,965**

(22) Filed: **Sep. 8, 2021**

(51) LOC (14) Cl. **06-09**

(52) U.S. Cl.

USPC **D6/601**

(58) **Field of Classification Search**

(74) Attorney, Agent, or Firm — MUNCY, GEISSLER, OLDS & LOWE, P.C.

(57) **CLAIM**

The ornamental design for a seat cushion, as shown and described.

DESCRIPTION

FIG. 1 is a perspective view of the seat cushion showing my new design;

FIG. 2 is a front view of the seat cushion;

FIG. 3 is a back view of the seat cushion;

FIG. 4 is a left side view of the seat cushion;

FIG. 5 is a right side view of the seat cushion;

FIG. 6 is a top view of the seat cushion; and,

FIG. 7 is a bottom view of the seat cushion.

1 Claim, 5 Drawing Sheets
